(57) **CLAIM**

The ornamental design for a modular travel pillow set, as shown and described.

DESCRIPTION

FIG. 1 is a perspective view of the modular travel pillow set. FIG. 2 is a top view of the modular travel pillow set. FIG. 3 is a bottom view of the modular travel pillow set. FIG. 4 is a front view of the modular travel pillow set. FIG. 5 is a rear view of the modular travel pillow set. FIG. 6 is a right view of the modular travel pillow set. FIG. 7 is a left view of the modular travel pillow set; and, FIG. 8 is a perspective view of the modular travel pillow set rolled up.

All broken lines shown in FIGS. 1–7 are used to show stitching of the modular travel pillow set or the creasing effects of fabric or fibrous material. The broken lines do not form part of the claimed design.

1 Claim, 5 Drawing Sheets(56)
